US00D724020S

(12) **United States Design Patent**
Kwon et al.

(10) **Patent No.:** **US D724,020 S**
(45) **Date of Patent:** **** Mar. 10, 2015**

(54) **BATTERY FOR PORTABLE TERMINAL**

(71) Applicant: **LG Chem, Ltd.**, Seoul (KR)

(72) Inventors: **Sung-Jin Kwon**, Daejeon (KR);
Ki-Woong Kim, Daejeon (KR);
Dong-Myung Kim, Daejeon (KR)

(73) Assignee: **LG Chem, Ltd.** (KR)

(**) Term: **14 Years**

(21) Appl. No.: **29/497,787**

(22) Filed: **Jul. 29, 2014**

Related U.S. Application Data

(60) Division of application No. 29/479,546, filed on Jan. 17, 2014, now Pat. No. Des. 716,722, which is a continuation-in-part of application No. 29/466,068, filed on Sep. 4, 2013, now Pat. No. Des. 709,440.

CLAIM

The ornamental design for a battery for portable terminal, as shown and described.

DESCRIPTION

FIG. 1 is a front perspective view of a battery for portable terminal according to our design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Broken lines are environmental only and form no part of the claimed design.

Dash-dot lines adjacent shaded areas represent bounds of the claimed design and form no part of the claimed design themselves.

1 Claim, 4 Drawing Sheets
